UNITED STATES PATENT OFFICE.

KORK KELLEY, OF OKMULGEE, OKLAHOMA, ASSIGNOR OF ONE-HALF TO THOMAS L. KERR, OF BARTLESVILLE, OKLAHOMA.

PRODUCTION OF LIQUID MOTOR FUELS.

Application filed August 15, 1921. Serial No. 492,368.

To all whom it may concern:

Be it known that I, KORK KELLEY, a citizen of the United States, and a resident of Okmulgee, Oklahoma, have invented new and useful Improvements in the Production of Liquid Motor Fuels, which invention is fully set forth in the following specification.

The present invention relates to the production of a new product intended principally for use as a motor fuel.

Casinghead gas, as it is commonly known in oil regions, is a naturally formed gas coming from oil wells and consisting of hydrocarbon gases and readily liquefiable products. Ordinarily casinghead gas is utilized by condensing the liquefiable portions thereof to produce what is commercially known as casinghead gasoline which it has been the practice to transport in tank cars from the plants at which it is produced to different places of use, such as rubber plants, paint factories, and other places where it has heretofore been utilized in the manner presently explained in producing motor fuel. But the shipment and handling of casinghead gasoline in its raw state is very hazardous because of its low initial boiling point, its very high volatility, and its very high vapor tension, generating high pressures in the tank cars. Because of such hazardous characteristics it has been the practice of the casinghead gasoline industry, in an effort to at least lessen the hazard, to use specially constructed tank cars insulated against heat from atmospheric temperatures. Furthermore, because of the extreme volatility of said gasoline and the consequent dangers of fire and explosion, the loading and unloading of tank cars requires the services of experts especially skilled in the work. Casinghead gasoline, moreover, is not usable by itself as a motor fuel because of its extreme volatility, and also because of its light gravity it does not generate the requisite heat units.

One of the uses to which casinghead gasoline has been heretofore put is the mixing thereof with a heavier gasoline, or so-called naptha, resulting in the production of a commercial gasoline usable as a motor fuel and for domestic purposes. Such liquid fuel has been produced in very large quantities in the past, but owing to the increase in the price of naptha to a point now pro-

hibiting its use for that purpose, and also because of lack of production of naptha—the refineries now refusing to cut the naptha in fractionating the petroleum—it is no longer economical or practical to produce a commercial liquid fuel by the mixing of the casinghead gasoline and naptha. In fact, naptha alone has now advanced to a price in excess of high grade gasoline.

In view of the high cost of naptha and lack of production of the same, it is now the practice to produce and utilize mixtures of the casinghead gasoline with kerosene formed by putting the two together while both are in liquid form. But such product has decided disadvantages and objections and is quite unsatisfactory and inefficient as a motor fuel, due primarily to its high end-point (meaning the highest or maximum temperature reached in distilling a hydrocarbon oil) and resulting large amount of carbon it deposits in the ordinary motor of today because of incomplete and imperfect combustion. Another, and probably even more serious, objection to such kerosene-casinghead gasoline mixture is its susceptibility to separation or unmixing in transportation and storage, thus recreating the conditions of hazard and disadvantage hereinbefore mentioned with respect to casinghead gasoline. There is the further disadvantage that, accompanying such separation, there is a so-called "outage" or loss incurred due to evaporation. This percentage of loss frequently runs very high, causing embarrassing conditions arising from shipments; for example, a tank car started on its way to a distant point completely full, may arrive at its destination only partially full, the loss being due to the aforesaid separation and evaporation.

A principal object attained by the present invention is the provision of a motor fuel much cheaper in cost of production and equally, or even more, efficient than gasoline such as now used for automobiles. Another main object attained by the present invention is the production of a permanent blend from casinghead gasoline and a heavier hydrocarbon oil, such as kerosene, and the present invention comprises not only such new product but primarily the process by which the product is produced. Further objects are the provision of a process which

may be expeditiously and economically carried out with the result of producing the permanent blend of casinghead gasoline and hydrocarbon oil, such as kerosene, at a cost 5 far below the cost of production of ordinary refined gasoline. For example, kerosene is today practically a drug on the market and is obtainable at refineries at about one cent per gallon. Casinghead gasoline is producible at a cost of approximately four to 10 six cents a gallon, and sells around six cents a gallon. There is, however, very little demand for raw casinghead gasoline at any price so that it also is approximately a drug 15 on the market, like kerosene. Thus the initial cost of the ingredients of the new product which may be employed in producing this invention is very low, and with a correspondingly low cost of carrying out 20 the process of this invention, the new product is producible at a cost far below that of gasoline and can be marketed much cheaper and at a relatively greater profit.

My invention overcomes in large part, 25 and it is believed entirely, the aforesaid objections, defects and difficulties with respect to the prior mixtures employing casinghead gasoline, and secures the aforesaid objects by providing a blended product containing 30 casinghead gasoline, and by providing a method of preparing the same which consists, generally stated, in distilling or vaporizing a petroleum oil, such as kerosene for example, preferably under superatmospheric 35 pressure of an inert gas, such as casinghead gas, and at a temperature sufficient to fractionally distill or otherwise break up more or less of the kerosene oil, and while the more volatile portion of the kerosene oil 40 is being driven over or a vapor composed of the more volatile or lighter constituents of the kerosene oil is being formed, introducing and commingling with the vapor of the kerosene oil the vapor of casinghead 45 gasoline, and then condensing the blended vapors to a liquid.

In the accompanying drawing illustrating, 50 partly diagrammatically, a system of apparatus suitable for carrying out the new process,

Fig. 1 is a top plan view; and

Fig. 2 is a front elevation with some parts in vertical section on line 2-2 of Fig. 1.

55 5 and 6 are two oil stills of any suitable well-known construction, and each shown as having a fire chamber 7 and a chimney 8 both formed of concrete or other suitable material. Each still is provided with a 60 safety valve 9 and a dome 10 from which a vapor-conducting pipe 11 leads to a so-called "knock-out" box 12, which is a closed chamber shown in this instance as common to both stills, both pipes 11 leading thereto.

65 In said "knock-out" box or commingling chamber the vapors from the two stills commingle and in that form are led through a pipe 13 to a suitable condenser 19 which, in the form illustrated in the drawings, comprises coils of pipe 14 enclosed by a housing 70 made of louvre boarding so arranged as to retain water spray within the housing while permitting circulation of air. 15 is a valved return flow pipe or "run-back" leading from the bottom of the "knock-out" box 12 back 75 into the still 6. 16 is an outlet or discharge pipe leading from the exit end of the cooling coils 14 to a receiving tank 17, there being within said tank a baffle plate 18 (shown in dotted lines in Fig. 2) positioned 80 over the discharge end of pipe 16 to deflect the liquid from said pipe downward to the bottom of the receiver 17. 20 is a gas supply pipe from which valved branches 21, 21 lead into and along the bottom of the 85 stills 5 and 6 respectively, said branch pipes being perforated within the still, preferably at their bottom, for the distributed discharge of gas to agitate the contents of each 90 still as presently more fully described. 22 is a gas-conducting pipe leading from the top of receiver 17 to two valved branches 23, 23, said branches being provided with suitable burners located in the fire boxes 95 and under the stills 5 and 6 respectively. Near the receiver 17 the pipe 22 is provided with a pop-valve 24 which is set or tensioned to open only under a certain maximum pressure and to thereby hold the pressure 100 in the system up to the desired point. 25 is a branch pipe leading from the pipe 22 and provided at its outer end with a relief valve 26. 27 is an outlet pipe leading from the bottom of receiver 17 to conduct the 105 liquid product to suitable storage tanks not shown. The process constituting the invention may of course be carried out in other suitable arrangements of apparatus though that illustrated is the one at this time preferred by me.

In using the aforesaid apparatus to carry out the process and produce the product of this invention, the procedure may be as follows:—Still 6 is charged with a suitable 110 hydrocarbon oil or petroleum distillate, for example kerosene, and still 5 is charged with casinghead gasoline, the amount of each being determined by the quality or gravity of the desired finished product; in other words, the gravity of the final product may be 115 varied by varying the relative proportions of the two commingled vapors coming from the separate stills. By way of a specific example, 500 gallons of casinghead gasoline of 120 80 B. are introduced into still 5, and 500 gallons of petroleum product such as W. W. kerosene of 42 B. are introduced into still 6. The stills are then fired and distillation 125 continued, preferably under super-atmospheric 130

pressure, for example about 30 pounds, until practically all of the casinghead gasoline has been vaporized and about 50% of the kerosene oil has been vaporized, when the heat is cut off. The vapors formed in the stills 5 and 6 are led by the pipes 11 to the "knock-out" box 12 in which they are intimately commingled. From the "knock-out" box 12 the commingled vapors are conducted through pipe 13 to and through the coils 14 of the condenser and thence through the pipe 16 into the receiver 17. Vapors condensed in the "knock-out" box 12 flow through the pipe 15 back into the still 6 for further heating. The liquefied vapors which are condensed and collected in receiver 17 will be found to have a gravity of about 66 B. The residue in still 6 is then withdrawn and the stills are then ready for a new charge.

During the firing of the stills hydrocarbon gas may be introduced into the stills through the pipe 20 and its perforated branches 21, 21, but is not essential, such injection of gas when used serving to agitate the liquid contents of both stills and thereby preventing excessive local heating and also serving as a vehicle for carrying the vapors through the system. When this gas, bearing the liquid condensate of the commingled vapors, reaches the receiver 17, the gas is there separated from said condensate, and may be conducted from the top of said receiver through the pipe 22 to the burners under the stills where it is utilized and combusted as fuel for heating the stills. In passing through pipe 22 the gas must pass the pop-valve 24 which serves to hold the required pressure on the system, the maintaining of such pressure back onto the surface of the kerosene in the still 6 serving to hold back the heavier hydrocarbons for further heating. When the gas passing from receiver 17 into pipe 21 is more than required for consumption at the burners or exceeds the predetermined pressure to be maintained in the system, excess gas may be discharged to the atmosphere or elsewhere through branch pipe 25 and its escape valve 26.

As the result of the aforesaid distilling of the casinghead gasoline in still 5 its vapors are carried over into the "knock-out" box 12. And simultaneously therewith, as the result of the heating of still 6, the vapor products resulting from the heat treatment of the kerosene oil are carried over in lighter fractions into the "knock-out" box and there commingled with the vapors from still 5. The vapors from the two stills by being thus commingled in vapor form in the "knock-out" box 12 bring about a temperature and vapor blend, the vapors from each of the stills coming over in fractions and commingling together, and such action constituting a very important feature of the inven-

tion. Care should be taken to fire the stills gradually and slowly so as to avoid overheating.

The new product or condensate is a refined product containing redistilled casinghead gasoline blended in a permanent manner with the distilled products of the heavier oil. This new product is not only superior in fuel qualities to the aforesaid prior mixtures of casinghead gasoline with naphtha, or kerosene, but it is also superior to commercial refined gasoline. It possesses distinctive characteristics amongst which may be noted the peculiar character of its distillation curve, its relative freedom from the offensive and disagreeable odors of commercial gasoline, its clean burning qualities due to the absence of heavy hydrocarbons, and the permanence of the blend, certainly for such period of time as would ordinarily elapse between production and consumption.

The aforesaid apparatus and procedure may be varied in carrying out the process and producing the product without departing from the present invention.

What I claim is:

1. The method of producing a hydrocarbon oil consisting in vaporizing kerosene under pressure, introducing into and blending with said vapors casinghead gasoline vapor, and condensing said blended vapors to a fluid state.
2. The method of producing a hydrocarbon oil consisting in vaporizing kerosene under pressure and temperature sufficient to fractionally distill the latter, introducing into and blending with said vapors casinghead gasoline vapor, and condensing said blended vapors to a liquid state.
3. The method of producing a hydrocarbon oil consisting in separately distilling casinghead gasoline and only the more volatile portions of a product of petroleum oil, commingling the resulting vapors, and condensing said blended vapors to a liquid state.
4. The method of producing a hydrocarbon oil consisting in commingling the separate vapors of casinghead gasoline and only the more volatile constituents from a product of petroleum oil, and condensing said vapors to a liquid state.
5. The method of producing a hydrocarbon oil consisting in vaporizing kerosene under pressure of an inert gas, introducing casinghead gasoline vapor into said vapor and gas, and condensing said vapors to a liquid state.
6. The method of producing a hydrocarbon oil consisting in vaporizing a petroleum oil of a density heavier than casinghead gasoline under pressure of an inert gas and at a temperature requisite to fractionally distill said oil, introducing into and blending with the resulting vapors, casinghead gaso-

- line vapor, and condensing the commingled vapors to a liquid.
7. The method of making a hydro-carbon oil which includes commingling the vapor of casinghead gasoline and a vapor separately derived from only the more volatile portions of a heavier hydro-carbon oil, and condensing the commingled vapors.
8. The method of making a hydro-carbon oil which includes distilling casinghead gasoline, distilling a heavier hydro-carbon oil but discontinuing the distillation before all of the oil is vaporized, commingling their vapors, and condensing the commingled vapors.
9. The method of making a hydro-carbon oil which includes distilling casinghead gasoline, fractionally distilling a heavier hydro-carbon oil, commingling the distilled vapors, and condensing the commingled vapors.
10. The method of making a hydro-carbon oil which includes distilling casinghead gasoline, distilling a heavier hydro-carbon oil under pressure, commingling the distilled vapors, and condensing the commingled vapors.
11. The method of making a hydro-carbon oil which includes distilling casinghead gasoline, fractionally distilling a heavier hydro-carbon oil under pressure, commingling the distilled vapors, and condensing the commingled vapors.
12. The method of making a hydro-carbon oil which includes separately distilling casing head gasoline and a heavier hydro-carbon oil while agitating the same by the introduction of gas, commingling the distilled vapors and gas, and condensing the commingled vapors from the gas.
13. The method of making a hydro-carbon oil which includes separately distilling both casinghead gasoline and a heavier hydro-carbon oil under pressure, commingling the distilled vapors, and condensing the commingled vapors.
14. The method of making a hydro-carbon oil which includes separately distilling casinghead gasoline and a heavier hydro-carbon oil, commingling the distilled vapors while maintaining a pressure thereon, and condensing the commingled vapors.
15. The method of making a hydro-carbon oil which includes commingling the vapor of casinghead gasoline and a vapor separately derived from only the more volatile portion of kerosene, and condensing the commingled vapors.
16. The method of making a hydro-carbon oil which includes distilling casinghead gasoline, distilling kerosene but discontinuing the distillation before all of the kerosene is vaporized, commingling their vapors, and condensing the commingled vapors.
17. The method of making a hydro-carbon oil which includes distilling casinghead
- gasoline, fractionally distilling kerosene, commingling the distilled vapors, and condensing the commingled vapors.
18. The method of making a hydro-carbon oil which includes distilling casinghead gasoline, distilling kerosene under pressure, commingling the distilled vapors, and condensing the commingled vapors.
19. The method of making a hydro-carbon oil which includes distilling casinghead gasoline, fractionally distilling kerosene under pressure, commingling the distilled vapors, and condensing the commingled vapors.
20. The method of making a hydro-carbon oil which includes separately distilling casinghead gasoline and kerosene while agitating the same by the introduction of a gas, commingling the distilled vapors and gas, and condensing the commingled vapors from the gas.
21. The method of making a hydro-carbon oil which comprises separately distilling both casinghead gasoline and kerosene under pressure, commingling the distilled vapors, and condensing the commingled vapors.
22. The method of making a hydro-carbon oil which includes separately distilling casinghead gasoline and kerosene, commingling the distilled vapors while maintaining a pressure thereon, and condensing the distilled vapors.
23. The method of making a hydrocarbon oil which includes distilling casinghead gasoline, subjecting a heavier hydrocarbon oil to heat to drive over only the lighter constituents thereof, commingling the vapors derived from both said gasoline and said oil, and condensing the commingled vapors.
24. The method of making a hydrocarbon oil which includes distilling casinghead gasoline, subjecting kerosene to heat to drive over only the lighter constituents thereof, commingling the vapors derived from both said gasoline and said kerosene, and condensing the commingled vapors.
25. The method of producing a hydrocarbon oil consisting in vaporizing kerosene oil under pressure and temperature sufficient to form a vapor composed of only the more volatile constituents of said oil, introducing into and blending with said vapors casinghead gasoline vapor, and condensing the blended vapors.
26. The method of producing a hydrocarbon oil consisting in vaporizing a product of petroleum oil under pressure and temperature sufficient to form a vapor composed of only the more volatile constituents of said oil, introducing into and blending with said vapors casinghead gasoline vapor, and condensing the blended vapors.

In testimony whereof I have signed this specification.

KORK KELLEY.
